UNITED STATES PATENT OFFICE

EDGAR B. SYMONS, OF HOLLYWOOD, CALIFORNIA, ASSIGNOR TO NORDBERG MANUFACTURING COMPANY, OF MILWAUKEE, WISCONSIN, A CORPORATION OF WISCONSIN

CRUSHING APPARATUS

Original application filed February 20, 1929, Serial No. 341,336. Divided and this application filed July 11, 1930. Serial No. 467,237.

My invention relates to a crushing device, and particularly to an improvement in crushing devices in which a cone is gyrated in a normally fixed concave or bowl.

5 One object of my invention is to provide a bowl, and supporting means therefor, which shall be normally maintained in fixed position but which shall be adapted to yield to a predetermined pressure in excess of normal 10 crushing pressure or to permit the passage through the space between cone and bowl of uncrushable material. Another object is the provision of improved yielding means or members whereby this yielding is permitted. 15 Another object is to provide an improved lubricating means and dust preventing means for a cone crusher of the type described. Other objects will appear from time to time in the course of the specification and claims. 20 The present application is a division of my co-pending application 341,336, filed on February 20, 1929.

I illustrate my invention more or less diagrammatically in the accompanying drawings, wherein—

Figure 1 is a vertical axial section;

Figure 2 is a horizontal section on the line 2—2 of Figure 1; and

30 Figures 3 and 4 are partial horizontal sections through variant forms of my device.

Like parts are indicated by like symbols throughout the specification and drawings.

Referring to the drawings, A generally indicates the main frame of a crushing device 35 which may be formed at the bottom of any suitable base A¹, secured to a supporting surface, for example by the bolts A². A main frame section is shown, as in Figure 2, as cylindrical in cross-section. It is illustrated as terminating at its upper edge in a flange B, the top of which is inwardly beveled as at B¹ and outwardly beveled as at B² to receive the upper frame section or ring, generally indicated as C. The flange B projects outwardly 45 from the body A of the frame. Or, stating it otherwise, the body or frame A is recessed within the outer periphery of the flange B. The purpose of this recessing or offset will later appear. The member C is provided 50 with a laterally extending flange or flanges

C¹, outwardly extending from the generally cylindrical portion C², the cylindrical portion being inwardly screw-threaded as at C³. The flange or flanges C¹ are provided with the beveled surfaces C⁴ and C⁵, opposed to the beveled surfaces B¹ and B² of the portion B. 55

The member B is apertured to receive a plurality of aligning members, indicated as the pins D, with the flanges D¹ and the upwardly projecting portions D² shown as slightly tapered and rounded at the tip. 60

Positioned about the main frame A are a plurality of groups of springs E. The tops and bottoms of said springs are compressed between a plurality of sets of abutment members or segments, an upper abutment E¹ and a lower abutment E² being provided for each set of springs E. While I do not wish to be limited to any particular number or arrangement of springs, I have indicated, in Figure 2, 70 as a practical arrangement, a plurality of sets of springs, five springs to a set, the springs being arranged in staggered relation with three springs arranged in an arc adjacent the face of the main frame and two springs positioned more distantly therefrom. In order to maintain the compression of the springs and to provide a bond between the lower abutment E² and the member C¹, I employ a plurality of bolts E³ for each set of springs, said 75 bolts being held at the top as at E⁴ and being provided at the bottom with locking and adjusting nuts E⁵, whereby the compression of the springs may be controlled. As an illustration, I have indicated three such bolts E³ 80 for each group of springs, two of said bolts being aligned with surrounding springs. 85

The member D serves to center the other of said springs, and it will be understood that, where necessary, axial lugs or plugs, such as E⁶, are employed to maintain the springs properly aligned. E⁷ indicates an outer rim about each such abutment member E¹ or E². It will be observed, as in Figure 1, that the effect of the spring assembly will be 90 to draw the flange or rings C¹ downwardly against the flange or ring B, and to maintain the frame portion C² fixed in position in relation to the frame A. 95

In screw-threaded relation to the spring 100

C² is the bowl or concave supporting frame, generally indicated as G. It includes the cylindrical outer frame portion G¹, screw-threaded as at G² in opposition to the screw-threaded portion G³ of the member C². It will be understood that rotation of the member G¹ in relation to the member C raises and lowers the bowl or concave, the means for effecting such rotation and adjustment 10 being not indicated herein, since they form of themselves no part of the present invention. Inwardly and upwardly projecting from the lower edge of the member G¹ is the bowl support G⁴, which is connected to the outer portion G¹ as by the webs G⁴. The portion G⁴ is apertured as at G⁵ to permit the passage of securing lugs G⁷ upon the bowl proper G⁶. G⁸ indicates any suitable locking means whereby, by engagement with the lugs 15 G⁷, the bowl G⁶ can be brought up against the member G⁸. The details of these locking means are not described with greater fullness herein, being the subject of a co-pending application, No. 310,988, filed on the 8th day 20 of October, 1928.

Positioned upon the top of the member C² is a member, generally indicated as H. It includes a cylindrical portion H¹ and a generally horizontal top portion H², in which 25 are formed a plurality of apertured bosses H³, which receive the heads H⁴ of the bolts H⁵. H⁴ is a nut upon said bolt, adapted to engage the lateral flanges or projections H⁷ which is associated with the member G, 30 whereby the tightening of the bolt H⁵ will draw the member H downwardly against the upper edge of the frame member C², or rather, will raise the member G, in relation to C². It will be understood that the members H⁷ project into pockets in the member H, whereby relative rotation of the members G and H is prevented.

Positioned within the inner periphery of the portion H² of the housing H is a cylindrical member J, within which is a hopper formed of segments J¹ resting upon a hopper shaped supporting surface J², which in turn is secured to the upper edge of the portion G³, as by the bolts J⁴. The details of this hopper structure do not, of themselves, form a part of the present invention and will not be further considered. The ring J⁵ may be employed to engage the tops of the segments J¹, to hold them in position, the ring J⁵ being 50 held by the straps or abutments J⁶ bolted as at J⁷ to the upper edge of the ring J. A wiping member J⁸ is provided intermediate the ring J and the housing H.

K generally indicates a generally cylindrical bearing sleeve associated with the main frame A and lying in the vertical axis thereof. Positioned therewithin is the eccentrically apertured sleeve K¹, associated with the gear K², which, meshing with the driving gear K³, may be rotated from any suitable 55

power source not herein shown. The crushing shaft K⁴ penetrates the eccentric aperture K⁵ of the sleeve K¹ and is gyrated in response to the rotation of said sleeve.

L generally indicates the bearing and guard member positioned above the sleeve K. It is indicated as having an upper spherical bearing surface L¹, and is surrounded by the oil-sump or peripheral passage L². The discharge passage L³ is in communication with the space formed by the gear box K¹⁰ about the gear K². L⁴ indicates a flange extending outwardly from the sump L² and having an upper spherical bearing surface L⁵ and a lower spherical bearing surface L⁶, both said 70 surfaces being preferably concentric with the main spherical bearing surface L¹. L⁷ indicates an oil groove in the face of the surface L⁵, provided with passages L⁸ extending to the bottom of the oil lamp. L⁹ indicates an 75 overhang or lip adapted to prevent any retrograde flow of lubricant to the bearing M¹.

M generally indicates a cone mounted on the upper end of the shaft K⁴ and is provided with a spherical bearing surface M¹, 80 conforming to and resting upon the surface L¹. M² indicates an axial oil passage in the shaft K⁴, which is in communication with the lateral passage M³ with the oil induct M⁴ extending to the lower bearing surface M¹. 85 It there communicates with the circumferential oil passage M⁵, which in turn communicates with the radial passage M⁶ extending to the wall of the shaft K⁴, and being adapted to deliver oil downwardly along said shaft 90 to the gear box K¹⁰ or to the bearing surface between shaft and eccentric sleeve. The crushing head M is provided with the outer 95 conic surface portion, generally indicated as M⁷, and terminating at its lower edge in the downwardly extending apron M⁸. M⁹ indicates an inner apron positioned exteriorly of the surface M¹. The members M⁸ and M⁹ 100 have opposed parallel surfaces, indicated as M¹⁰ and M¹¹, within which slides the oil wiping member generally indicated as O, and having the flange O¹ and a spherical bearing surface opposed to the surface L⁵ and a lower flange O² opposed to the surface L⁶. Any 105 suitable means, for example the springs O³, are employed for thrusting the member O downwardly and for maintaining its upper member O¹ closely opposed to the upper bearing surface L⁵ of the member L⁴.

Positioned upon the head M⁷ is any suitable mantle P, shown in conic form, with the upwardly extending central hub or top portion P¹ adapted to be engaged by the annular abutment P² controlled by the lock nut P³ screw-threaded, as at P⁴, to the upper 110 screw-threaded extension K¹¹ of the shaft K⁴. The portion P³ is provided at its upper end with an outwardly extending circumferential flange P⁵, upon which is positioned any suitable feed limiting or feeding plate P⁶. The 115

details whereby the lock nut P^3 is held against rotation, in such fashion that the mantle is clamped upon the cone, do not, of themselves, form part of the present invention and need not be considered in detail.

5 It will be realized that whereas I have described and shown a practical and operative device, nevertheless many changes might be made in the size, shape, number and disposition of parts without departing from the spirit of my invention. I therefore wish my drawings to be taken as, in a broad sense, illustrative and diagrammatic, rather than as limiting me to the specific features herein described and shown, except so far as I limit 10 myself by the language of the claims.

15 The use and operation of my invention are as follows:

The invention relates to an improvement 20 in cone crushers of the type wherein a spring release is provided for the bowl. In the larger size of crushers it is important that a sufficient number of springs be spaced about a bowl to hold it in position against all but 25 excess crushing strains. I find it desirable to arrange the springs in a plurality of groups and to arrange the springs in each group at varying distances from the axis of the machine. These groups of springs are 30 of sufficient power to hold the ring C^1 clamped firmly downwardly against the top of the frame A. On the other hand, if uncrushable material, such as tramp iron or caked stone, passes through the device, the 35 springs are of such strength and set at such compression as to give sufficiently to prevent breakage or stoppage of the machine and to pass the troublesome substance or body. When the bowl and its support tilt upwardly 40 to permit the passage of such material, the member C^1 is lifted from the member B. The bolts E^3 tend to maintain the alignment 45 of the devices, but I prefer to employ, also, the pin or aligning members D, the upper ends D^1 of which insure that the member C^1 will not escape from its proper alignment and will not rotate in relation to the member B. Such rotation, of course, throws a strain upon the bolts and springs.

50 Whereas I have described and shown a particular arrangement of springs in groups, it will be understood that I do not wish to be limited specifically to it, except so far as I do limit myself in my claims and in particular I may employ a concentric arrangement of springs, two or more springs being positioned about the individual guides or bolts E^3 or about the members E^6 , as shown in Figures 3 and 4. I have indicated in 55 Figure 3 a form of my device in which I employ the inner spring R and the outer spring R^1 about each bolt or abutment. In the form of Figure 4 I illustrate a third external spring F^2 , about the other two. It 60 will be realized that whereas I have illus- 65

trated these multiple springs as shown in connection with segments E^2 that they may be applied independently of such segments, with any suitable means for guiding and centering them or for grouping them, when they 70 are arranged in groups. The group arrangement is convenient but may not under all circumstances be necessary.

The member H is in effect a housing ring, 75 and prevents the access of dust to the parts within it. It serves other primary purposes, however. The lateral projections H^7 , as above described, prevent any relative rotary movement of the member H and the member G. Therefore the ring H may act as 80 a wrench for turning the bowl G within the ring C. Any suitable means for causing rotation of the ring H, such means being not shown herein in detail, have for effect to rotate the member G and to cause the member G to raise or lower within the screw-threaded ring C^2 . Assuming that the rotation is in such direction as to cause the member G to rise, it rises in relation to the member H which rests normally upon the top of 85 the member C^2 , upwardly projecting from the frame member C. The wiping member or washer J^8 provides a substantial dust proof connection between the inwardly projecting flange H^2 and the cylindrical member J about 90 the hopper.

The bolts H^5 , with their nuts H^6 , serve to 95 raise the member G, through the projections H^7 , to relieve the contact of the threads on the opposed members G^1 and C^2 . These threads are made with considerable play, and the act of crushing stone will lift the threads on the member G^2 and cause them to bind to the extent of the play between them and the opposed threads. It is in order to take 100 up this play that the bolts H are introduced. By tightening the bolts H after the correct setting has been obtained, the play is taken up, as to the loose threads. The nuts H^6 lift up on the bowl and the ring H exerts 105 a downward pressure upon the top of the member C^2 .

The washers H^{10} may be made of fiber and 110 may be interposed between steel washers, one above and one below. The washers H^{10} may for example be made of pieces of rubber belting. If a piece of steel goes through the crushing cavity, it causes the ring C to be raised in relation to the member A, this tilting yielding release being important to prevent breakage of the device. As soon as the head recedes and the steel, or other uncrushable substance, as pass from the crushing cavity, there will be a pronounced blow when 115 the ring member C seats itself on the frame as at C^5 . It is the function of the washers H^{10} to absorb or cushion this shock. In practice they furnish sufficient pressure to keep the threads in contact, so that there will be 120 no pounding but they give sufficiently to prevent 125 no pounding but they give sufficiently to prevent 130

vent stripping the threads on the bolts H^6 .

The cone M is mounted upon a spherical bearing surface L^1 , and this bearing surface is protected from the penetration of dust or 5 the like, which would shortly wear it out, firstly by the circumferential oil sump and secondly by the outer guard member L^6 with its inner and outer spherical bearing surfaces in engagement with the inner and outer 10 flanges of the dust guard member O .

The hopper above the cone is preferably formed of a plurality of removable, and preferably separately removable segments J^1 . These segments or liners are subjected to 15 heavy wear and may be made of manganese steel, being of course easily replaceable and being held in place for example upon the conic ring or supporting surface J^2 , being held in position either by their form and 20 inter-engagement, or by the rearward projections J^{10} which may project through the slots J^{11} of the member J^2 . The ring J^5 serves to hold them against upward movement.

I claim:

25 1. In a gyratory crusher including a cone and means for gyrating it, a concave spherical surfaced main bearing member, the under side of the cone being formed to conform thereto, a second bearing surface positioned exteriorly of and concentric with the main bearing surface and a closure ring member, mounted on said cone, in engagement with 30 said second bearing surface, and means for thrusting said ring downwardly against said bearing surface.

2. In a gyratory crusher including a cone and means for gyrating it, a concave spherical surfaced main bearing member, the under side of the cone being formed to conform 40 thereto, a second bearing surface positioned exteriorly of and concentric with the main bearing surface and a closure ring member, mounted on said cone, in engagement with said second bearing surface, the cone being 45 circumferentially recessed to receive said ring and means for thrusting said ring downwardly against said bearing surface.

3. In a gyratory crusher including a cone and means for gyrating it, a concave spherical surfaced main bearing member, the under 50 side of the cone being formed to conform thereto, a circumferential oil sump surrounding said bearing surface, a second bearing surface positioned exteriorly of said oil sump and concentric with the main bearing surface and a closure ring member, mounted on said cone, in engagement with said second bearing surface, the cone being circumferentially recessed to receive said ring and means for 55 thrusting said ring downwardly against said bearing surface.

4. In a gyratory crusher including a cone and means for gyrating it, a concave spherical surfaced main bearing member, the under 60 side of the cone being formed to conform

thereto, a second bearing surface positioned exteriorly of and concentric with the main bearing surface and a closure ring member, mounted on said cone, in engagement with said second bearing surface, and yielding 70 means for thrusting said ring downwardly against said bearing surface.

5. In a gyratory crusher which includes a cone and means for gyrating it, a concave spherical surfaced main bearing member, the 75 under side of the cone being formed to conform thereto, a second bearing member positioned exteriorly of the main bearing surface, said second member being provided with upper and lower spherical bearing surfaces concentric with said main bearing surface, and a closure member associated with 80 said cone, and bearing surfaces thereon in engagement with the upper and lower bearing surfaces of said second bearing member. 85

6. In a gyratory crusher which includes a cone and means for gyrating it, a concave spherical surfaced main bearing member, the under side of the cone being formed to conform thereto, a second bearing member positioned exteriorly of the main bearing surface, said second member being provided with upper and lower spherical bearing surfaces concentric with said main bearing surface, and a closure member movably mounted 90 upon said cone, and bearing surfaces thereon in engagement with the upper and lower bearing surfaces of said second bearing member. 95

7. In a gyratory crusher which includes a cone and means for gyrating it, a concave spherical surfaced main bearing member, the under side of the cone being formed to conform thereto, a second bearing member positioned exteriorly of the main bearing surface, said second member being provided with upper and lower spherical bearing surfaces concentric with said main bearing surface, and a closure member movably mounted 100 upon said cone, and bearing surfaces thereon in engagement with the upper and lower bearing surfaces of said second bearing member. 105

8. In a gyratory crusher which includes a cone and means for gyrating it, a concave spherical surfaced main bearing member, the under side of the cone being formed to conform thereto, a second bearing member positioned exteriorly of the main bearing surface, said second member being provided with upper and lower spherical bearing surfaces concentric with said main bearing surface, and a closure member movably mounted 110 upon said cone, and bearing surfaces thereon in engagement with the upper and lower bearing surfaces of said second bearing member, and means for thrusting said closure member downwardly against said second bearing member. 115

120

closure member downwardly against said second bearing member.

9. In a gyratory crusher including a cone and means for gyrating it, a concave spherical surfaced main bearing member, the under side of the cone being formed to conform thereto, a circumferential oil sump surrounding said bearing surface, a second bearing surface positioned exteriorly of said oil sump and a closure member, associated with said cone, adapted to engage said second bearing surface, the inner wall of the sump being formed with an overhanging lip.

10. In a gyratory crusher, a frame member, a cone and means for gyrating it, a bowl surrounding said cone, a supporting member for said bowl mounted upon said frame member and tilttable in relation thereto, and yielding means for holding said supporting member normally fixed in relation to said frame, said means including a plurality of sets of springs positioned about said frame member, individual abutment segments engaging the tops and bottoms of the springs of each set and members associated with each such set and with such abutments, adapted to maintain said springs under compression.

11. In a gyratory crusher, a frame member, a cone and means for gyrating it, a bowl surrounding said cone, a supporting member for said bowl mounted upon said frame member and tilttable in relation thereto, and yielding means for holding said supporting member normally fixed in relation to said frame, said means including a plurality of sets of springs positioned about said frame member, individual abutment segments engaging the tops and bottoms of the springs of each set and members associated with each such set and with such abutments, adapted to maintain said springs under compression, said sets of springs being positioned exteriorly of said frame member.

12. In a gyratory crusher, a frame member, a cone and means for gyrating it, a bowl surrounding said cone, a supporting member for said bowl mounted upon said frame member and tilttable in relation thereto, and yielding means for holding said supporting member normally fixed in relation to said frame, said means including a plurality of sets of springs positioned about said frame member, individual abutment segments engaging the tops and bottoms of the springs of each set and members associated with each such set and with such abutments, adapted to maintain said springs under compression, the springs of each such set being arranged about the exterior of the frame, some of said springs being positioned closely adjacent said exterior and others being spaced more distantly therefrom.

13. In a gyratory crusher, a frame member, a cone and means for gyrating it, a bowl surrounding said cone, a supporting member

for said bowl mounted upon said frame member and tilttable in relation thereto, and yielding means for holding said supporting member normally fixed in relation to said frame, said means including a plurality of sets of springs positioned about said frame member, individual abutment segments engaging the tops and bottoms of the springs of each set and members associated with each such set and with such abutments, adapted to maintain said springs under compression, the springs of each such set being arranged about the exterior of the frame, some of said springs being positioned closely adjacent said exterior and others being spaced more distantly therefrom, said more distant springs being staggered in the intervals between those close to the frame.

14. In a gyratory crusher, a frame member, a cone and means for gyrating it, a bowl surrounding said cone, a supporting member for said bowl mounted upon said frame member and tilttable in relation thereto, and yielding means for holding said supporting member normally fixed in relation to said frame, said means including a plurality of sets of springs, said springs being positioned about the exterior of the frame member, the frame member being recessed to receive them.

15. In a gyratory crusher, a frame member, a cone and means for gyrating it, a bowl surrounding said cone, a supporting member for said bowl mounted upon said frame member and tilttable in relation thereto, and yielding means for holding said supporting member normally fixed in relation to said frame, said means including a plurality of sets of springs, said springs being positioned about the exterior of the frame member, the frame member being recessed to receive them, and individual abutment segments engaging the tops and bottoms of each said set of springs and members associated with such segments, adapted to maintain the springs of the individual sets under compression.

16. In a gyratory crusher, a cone and means for gyrating it, a bowl surrounding said cone, a frame member upon which said bowl is mounted, a screwthreaded adjusting connection between said bowl and said frame member and means for rotating said bowl, including a ring positioned above said frame member and about said bowl and in non-rotatable relation with said bowl.

17. In a gyratory crusher, a cone and means for gyrating it, a bowl surrounding said cone, a frame member upon which said bowl is mounted, a screwthreaded adjusting connection between said bowl and said frame member and means for rotating said bowl, including a ring positioned above said frame member and about said bowl and in non-rotatable relation with said bowl, the connection between said ring and bowl being adapted to permit relative non-rotary move-

ment thereof along a generally vertical axis.

18. In a gyratory crusher, a cone and means for gyrating it, a bowl surrounding said cone, a frame member upon which said bowl is mounted, a screwthreaded adjusting connection between said bowl and said frame member and means for rotating said bowl, including a ring positioned above said frame member and about said bowl and in non-rotatable relation with said bowl, and means associated with said ring adapted to relieve the pressure upon said screwthreaded adjusting connection and to take up the play of the screwthreads thereof.

19. In a gyratory crusher, a cone and means for gyrating it, a bowl surrounding said cone, a frame member upon which said bowl is mounted, a screwthreaded adjusting connection between said bowl and said frame member and means for rotating said bowl, including a ring positioned above said frame member and about said bowl and in non-rotatable relation with said bowl, and means associated with said ring adapted to relieve the pressure upon said screwthreaded adjusting connection and to take up the play of the screwthreads thereof, said means including bolts depending from said ring and in engagement with said bowl.

20. In a gyratory crusher, a cone and means for gyrating it, a bowl surrounding said cone, a frame member upon which said bowl is mounted, a screwthreaded adjusting connection between said bowl and said frame member and means for rotating said bowl, including a ring positioned above said frame member and about said bowl and in non-rotatable relation with said bowl, and means associated with said ring adapted to relieve the pressure upon said screwthreaded adjusting connection and to take up the play of the screwthreads thereof, said means including bolts depending from said ring and in engagement with said bowl, and shock-taking members associated with said bolts.

21. In a gyratory crusher, a cone and means for gyrating it, a bowl surrounding said cone, a frame member upon which said bowl is mounted, a screwthreaded adjusting connection between said bowl and said frame member and means for rotating said bowl, including a ring positioned above said frame member and about said bowl and in non-rotatable relation with said bowl, and means associated with said ring adapted to relieve the pressure upon said screwthreaded adjusting connection and to take up the play of the screwthreads thereof, said means including bolts depending from said ring and in engagement with said bowl, and yielding washers associated with said bolts.

22. In a gyratory crusher, a cone and means for gyrating it, a bowl surrounding said cone, a screwthreaded supporting mem-

ber for said bowl, said bowl being screwthreaded to conform thereto, and means, associated with said supporting member, for relieving the pressure upon said screwthreads.

23. In a gyratory crusher, a cone and means for gyrating it, a bowl surrounding said cone, a screwthreaded supporting member for said bowl, said bowl being screwthreaded to conform thereto, and means, associated with said supporting member, for relieving the pressure upon said screwthreads, such means including a member adapted to engage and be supported by said supporting member, and an adjustable connection between such last mentioned member and the bowl.

24. In a gyratory crusher, a cone and means for gyrating it, a bowl surrounding said cone, a screwthreaded supporting member for said bowl, said bowl being screwthreaded to conform thereto, and means, associated with said supporting member, for relieving the pressure upon said screwthreads, such means including a member adapted to engage and be supported by said supporting member, and supporting elements depending therefrom and adapted to engage and support said bowl.

25. In a gyratory crusher, a cone and means for gyrating it, a bowl surrounding said cone, a screwthreaded supporting member for said bowl, said bowl being screwthreaded to conform thereto, and means, associated with said supporting member, for relieving the pressure upon said screwthreads, such means including a member adapted to engage and be supported by said supporting member, supporting bolts depending therefrom and adapted to engage and support said bowl.

26. In a gyratory crusher, a cone and means for gyrating it, a bowl surrounding said cone, a screwthreaded supporting member for said bowl, said bowl being screwthreaded to conform thereto, and means, associated with said supporting member, for relieving the pressure upon said screwthreads, such means including a member adapted to engage and be supported by said supporting member, supporting bolts depending therefrom and adapted to engage and support said bowl, and yielding washers, associated with said bolts.

27. In a gyratory crusher, a frame member, a cone and means for gyrating it, a bowl surrounding the cone, a supporting member for the bowl mounted upon said frame member and tiltable in relation thereto, and yielding means for holding said supporting member normally fixed in relation to said frame, said means including a plurality of individual sets of springs, and an individual abutment member for each said set.

28. In a gyratory crusher, a frame member, a cone and means for gyrating it, a bowl

surrounding the cone, a supporting member for the bowl mounted upon said frame member and tiltable in relation thereto, and yielding means for holding said supporting member normally fixed in relation to said frame, said means including a plurality of individual sets of springs, and an individual abutment member being opposed to the lower ends of the springs of each such set, the upper ends abutting against the frame itself, the frame being outwardly offset to align with said springs.

10 29. In a gyratory crusher which includes a cone and means for gyrating it, supporting means for said cone, and a wiping connection for said cone, exterior to said supporting means, and adapted to prevent the access of foreign material thereto, said wiping connection including a closure ring member, a member opposed thereto, and yielding means for 15 maintaining said member in closing position against said opposed member.

20 30. In a gyratory crusher which includes a cone and means for gyrating it, supporting means for said cone, and a wiping connection for said cone, exterior to said supporting means, and adapted to prevent the access of foreign material to said supporting means, a bearing surface opposed to said closure 25 ring member and yielding means, interposed between the cone and the closure ring member, adapted positively to thrust said closure ring member downwardly against said opposed bearing surface.

30 31. In a gyratory crusher including a cone and means for gyrating it, a ball and socket support for the bottom of said cone, and a wiping connection for said cone, adapted to protect said ball and socket support, said wiping connection including a closure ring member mounted upon the cone, yielding means for positively thrusting it downwardly in relation to the cone, and a bearing member opposed to the closure ring member.

35 40 Signed at Hollywood, county of Los Angeles and State of California, this 14th day of June, 1930.

EDGAR B. SYMONS.
